UNITED STATES PATENT OFFICE.

GEORGE ALBERT LYON, OF PHILADELPHIA, PENNSYLVANIA.

AUTOMOBILE-BUFFER.

1,325,738.

Specification of Letters Patent. Patented Dec. 23, 1919.

Continuation in part of applications Serial No. 170,129, filed May 22, 1917, and Serial No. 236,513, filed May 25, 1918. This application filed June 22, 1918. Serial No. 241,308.

To all whom it may concern:

Be it known that I, GEORGE ALBERT LYON, a citizen of the United States, and resident of Philadelphia, Philadelphia county, Pennsylvania, have made a certain new and useful Invention Relating to Automobile-Buffers, of which the following is a specification, taken in connection with the accompanying drawing, which forms part of the same.

The invention in this case which is a continuation in part of my copending applications Serial No. 170,129, filed May 22, 1917, and Serial No. 236,513, filed May 25, 1918, that is, it contains subject-matter taken therefrom, relates to resilient or spring strip buffers for use on automobiles or similar vehicles. The buffer front or impact receiving member of the buffer may be formed of one or more strips of spring steel or resilient metal and may be supported by separate spring strip attaching members attached to the automobile frame and preferably having forwardly and outwardly curved portions which are removably connected to the impact receiving portion of the buffer adjacent its ends. In this way the buffer members may be disconnected for shipping purposes and may be packed into relatively small compass, and this is also facilitated by making the buffer front of a plurality of partially overlapping reinforcing resilient strips which also makes the buffer of adjustable width, although of course the attaching members may be adjustably connected to the spring strip buffer front so that by adjusting their relative position the buffer may have the distance between its attaching members adjusted so as to fit automobiles having different width frame members.

In the accompanying drawing showing in a somewhat diagrammatic way illustrative embodiments of the invention—

Figure 1 is a top view showing one embodiment.

Fig. 2 is a transverse section taken substantially along the line 2—2 of Fig. 1 to show one form of connecting member or clip.

Fig. 3 is a top view showing another embodiment.

Fig. 4 is a partial side view thereof showing the attaching member thereof taken along the line 4—4 of Fig. 3.

Fig. 5 is an enlarged transverse section showing the clip and coöperating members taken along the line 5—5 of Fig. 3.

Fig. 6 is a rear view of the clip and connected parts.

Fig. 7 is a top view showing another form of buffer.

Fig. 8 is an enlarged rear elevation showing another form of connecting clip.

Fig. 9 is a similar view showing still another form as used in Fig. 7; and

Fig. 10 is a transverse section showing the same and taken substantially along the line 10—10 of Fig. 7.

The impact receiving member or front member of the buffer may be made of adjustable width by forming it of overlapping members which are adjustably connected together in any suitable way so that by adjusting the extent to which these members overlap at the central portion of the buffer the total width of the impact receiving member can be correspondingly varied. It is desirable to form these impact receiving members of resilient spring steel strips having many times as great vertical as horizontal rigidity which can be conveniently done by giving the strips of spring steel six or eight times as great a vertical width as their thickness in a horizontal direction as explained in greater detail in the Lyon Patent 1,198,246, of September 12, 1916. As indicated in Fig. 1, the impact receiving members 4, 10 may be adjustably connected by the clips, 11, such as described and shown in detail in said patent, and in this way by having one of these clips adjacent one end 3 of the forward impact receiving member 4, for instance, its other end 5 may extend out a considerable distance beyond the end 9 of the other impact receiving member 10 so that these free outer ends 5 and 8 of these members may be arranged at the desired distance apart determined by the vehicle to which the device is to be attached and may extend into protective position in front of the vehicle wheels. It is also advantageous to have these impact receiving members bowed forwardly which increases the extent of their resilient yielding action under collision conditions and by making these members uniformly curved at least throughout their overlapping portions adjustment and connection of these two members may be correspondingly facilitated.

100
105
110

The buffer may also comprise rearwardly extending attaching members preferably formed of similar vertically rigid and horizontally yielding spring strip and these attaching members may be formed with a rearward portion adapted to be rigidly secured to the frame of the automobile or other vehicle while their forwardly and outwardly curved portions 6, 7 are preferably 5 formed with ends having substantially the same curvature as the adjacent parts of the impact receiving or front members so that they may be more readily secured thereto in adjusted position by suitable clips 11. By 10 making these connections adjustable the distance apart of the attaching members 1, 2, may be correspondingly varied to adapt the buffer for attachment to vehicles having frame or other supporting members at different distances apart. The construction of 15 the adjustably connecting member or clip is illustrated in Fig. 2. The ends 14 of this metallic clip 11 have a diagonal position so that the bolt 13 and nut 12 can tighten the 20 buffer strips 4, 10 within the clips in both a vertical and horizontal direction. Also by having these clip ends extend rearward and downward behind the buffer front or impact receiving member the bolt and clip ends are 25 very largely concealed so that the clips resemble mere bands.

The buffer shown in Fig. 3 may comprise a similar impact receiving member formed of the resilient spring steel strips 4, 10. The 30 central or overlapping portions of these front strips of the buffer may be adjustably connected by any suitable connecting members or clips and the contact ends of this buffer front may be detachably connected 35 to the coöperating contact or connector portions 40 of the separate attaching strips or members 1, 2 by suitable means, such for instance as the U-bolt connectors 15 illustrated. Both arms of these U-bolt connectors may as 40 indicated pass through suitable holes or openings in the coöperating connector portions of the buffer front strips and attaching strips and the nuts 16 on the threaded ends of these bolt arms may clamp the spring 45 strip members together in connection if desired with suitable lock washers 17. The use of such U-bolt connectors is advantageous in this connection because it furnishes a double security against the loosening of the 50 parts, the U-bolt still remaining in position if one of the nuts becomes loosened or even lost. These U-bolt attaching connectors coöperating with the attaching members of the buffer are also desirable because they 55 stiffen and align the two buffer members through which each arm of one of the connector devices passes so as to minimize or prevent vertical movement between them if the nuts are tightened. The attaching members 1, 2 may be secured to the automobile 60

frame in any suitable way and as indicated in Fig. 4 they may be formed with bent ends 22 provided with attaching openings or slots such as 23, 24 with which are adapted to coöperate such hook bolt connectors as are shown in the Lyon Patent 1,266,836, of May 21, 1918. 70

A simple and effective form of connecting clip or member for encircling and adjustably connecting bumper strips of this character is shown in greater detail in Figs. 5 and 6 as formed essentially of a single piece of round spring steel stock for instance. This clip 18 may be bent in suitable dies to the desired shape and size and may have 80 a tightening end 21 of any suitable shape to engage a coöperating tightening device, while the other end of this integral member may be formed with a coöperating preferably flattened tightening portion adapted to coöperate with the tightening nut 20 which may be used on the threaded tightening end of the clip and form a rigid clamping surface therefor which is preferably directly opposite the bumper strips, 4, 10 beneath. 85 As indicated in Fig. 6 this tightening portion 19 may be of substantially yoke form having a slot 25 in which the threaded tightening end of the clip is adapted to fit, the stock being forged or flattened from the point 31 to form this yoke. By forming the 90 clips of this character so that they have a fairly tight engagement with the buffer strips at their closed or U-shaped ends away from the threaded tightening end of the clip they may be screwed up so as to tightly 95 compress the buffer clips at both the tightening end of the clip and the other thereof, where a considerable resilient tightening action is secured so that a strong integral clip of forged metal can thus be produced which is very effective for this hard service. Fig. 100 8 shows another form of connecting clip of this general character in which the clip 41 is formed with a similar threaded tightening 105 end and with a coöperating flat tightening portion 38 of hook form which may have the hook end 40 extending in a more or less diagonal direction toward the closed end of the connecting clip and preferably overlapping the coöperating buffer strips 4, 10, so that the nut on this tightening hook member can clamp both coöperating parts of this flat tightening portion against the buffer strips. With this hook form of tightening 110 115 portion a diagonal slot 39 is formed into, which the threaded tightening end of the clamp may be forced during the bending and forging processes by which the clip is made and the hook positively prevents the 120 threaded tightening end moving away from the coöperating closed end of the clip on the opposite edge of the buffer strips. Still another form of integral connecting clip or member is shown in Figs. 9 and 10 as formed 125 130

of a piece of round stock 32 having the threaded tightening end 36 with which may coöperate the tightening nut 35 or lock washer 34 if desired. The other end of the 5 clip which may be of substantially circular cross section, if desired, is shown as bent around into the form of a loop 37 to inclose the threaded tightening end and the end 33 of this round stock may, if desired, be electrically welded or otherwise secured to the 10 body of the clip so as to positively prevent any opening action. This form of clip gives substantially the full strength of the stock and the two arms of the tightening loop 15 member give ample bearing on the buffer strips when the nuts are tightened.

In Fig. 7 the front or impact receiving member of the buffer may be of any suitable form or construction and it may advantageously be formed of a plurality of 20 more or less overlapping spring strips such as 26, 27, which as indicated in Fig. 3 may be forwardly bowed and may have substantially uniform curvature so as to give a 25 pleasing appearance to the finished buffer and allow lateral adjustment of these impact receiving members when it is desired to have a buffer of adjustable width to fit different width vehicle frames. Any suitable 30 connecting means may be used to connect these front members preferably in a vertically rigid manner and at the same time effecting the desired lateral adjustment of these spring strips when the buffer is to be 35 used on different automobiles. For this purpose the connecting clips 32, 34, such as 40 described in connection with Figs. 9 and 10 may be used adjacent the inner ends 39, 43, of these front impact receiving members 45 to clamp them to the coöperating spring strips. The spring strip attaching members, 1, 2 may have forwardly and outwardly curved portions bolted or otherwise connected to the ends of the impact receiving 50 members and either one of these sets of members may be formed with a resilient end loop portion to increase the resilience of the buffer. If desired these resilient end loops, such as 28, may be formed on the 55 ends of the impact receiving members which gives a pleasing appearance to the buffer and at the same time increases its resilient yielding action under collision conditions. The end loops may terminate in connector 60 portions, such as 30, which may extend substantially parallel to the adjacent front portion of the corresponding impact receiving member. Coöperating connector portions, such as 29, may be formed on the 65 attaching members so as to coöperate with and be strongly and rigidly secured to the connector portions of the impact receiving members when clamped or bolted thereto in any suitable way. U-bolt attaching connectors, such as 15, are desirable for this

purpose and as indicated they may extend through suitable holes in the coöperating connector portions of these spring strip members so as to not only frictionally hold them together, but to maintain them in substantial vertical alinement when the nuts 17 on the bolt shanks are screwed down on the lock washers 17, for example. It is not of course necessary to have the connector portions of the two coöperating strips to be 70 connected together formed with the same curvature throughout, and in some instances it is desirable to have one or more of the ends of these spring strip connector portions diverge more or less from the coöperating 75 buffer strip as in Fig. 7 for instance. This not only accommodates any slight change of angle of the parts due to lateral adjustment or to slight inaccuracies of contour, but also makes it possible to positively prevent rattling by forcing together by suitable 80 connecting members of U-bolt or other form these somewhat convex resilient strips and this form of connector contact portions may of course be used with the other forms 85 of buffers previously described, if desired.

This invention has been described in connection with a number of embodiments, forms, proportions, parts, arrangements, materials, methods of connection and use, to 90 the details of which disclosure the invention is not of course to be limited, since what is claimed as new and what is desired to be secured by Letters Patent is set forth in the 95 appended claims.

I claim—

1. The automobile buffer comprising a resilient front portion composed of two flat spring strip impact receiving members having forwardly bowed connected overlapping reinforcing portions, and having end connector portions to extend outward into protective position in front of the automobile wheels, coöperating spring strip attaching members having attaching ends provided with attaching openings adapted to be clamped to the automobile frame and having forwardly and outwardly curved portions and end connector portions coöperating with the connector portions of said impact receiving members and having approximately the same curvature and U-bolt connectors passing through apertures in said coöperating connector portions and bolting the same together and positively 110 maintaining them in substantial vertical alinement.

2. The automobile buffer comprising a resilient front portion composed of two flat spring strip impact receiving members having connected overlapping reinforcing portions, and having end connector portions to extend outward into protective position in front of the automobile wheels, coöperating spring strip attaching members having 115

120

125

130

attaching ends provided with attaching openings adapted to be clamped to the automobile frame and having forwardly and outwardly curved portions and end connector portions coöperating with the connector portions of said impact receiving members and U-bolt connectors engaging said coöperating connector portions and bolting the same together and positively 10 maintaining them in substantial vertical alinement.

3. The automobile buffer comprising a substantially uniformly curved forwardly bowed resilient front portion composed of flat strip, and having free end connector portions to extend outward into protective position in front of the automobile wheels, coöperating resilient strip attaching members having attaching ends provided with 15 attaching openings adapted to be clamped to the automobile frame and having forwardly and outwardly curved portions and end connector portions to be detachably connected to the connector portions of said impact receiving members and having approximately the same curvature and U-bolt connectors passing through a plurality of apertures in each of said coöperating connector portions and bolting the same together and promoting their vertical alinement. 20

4. The automobile buffer comprising a substantially uniformly curved forwardly bowed resilient front portion composed of flat strip and connector portions to extend outward into protective position in front of the automobile wheels, coöperating resilient strip attaching members having attaching ends provided with attaching openings 25 adapted to be clamped to the automobile frame and having forwardly and outwardly curved portions and end connector portions detachably connected to the connector portions of said impact receiving members and having approximately the same curvature and U-bolt connectors passing through a plurality of apertures in each of said coöperating connector portions and bolting the same together and promoting their vertical alinement. 30

5. The automobile buffer comprising a vertically rigid horizontally yielding spring strip front portion composed of a plurality of flat spring strip impact receiving members having forwardly bowed overlapping reinforcing portions, and having outer connector portions to extend into protective position adjacent the automobile wheels, coöperating vertically rigid spring strip attaching members adapted to be clamped to the automobile frame and having forwardly and outwardly curved portions and curved end connector portions coöperating with the connector portions of 55 said impact receiving members and having 60

approximately the same curvature and U-bolt connectors detachably connecting said coöperating connector portions of said front portion and attaching members and adjusting the distance between the rear 70 portions of said attaching members to enable them to fit automobile frames of different width.

6. The automobile buffer comprising a resilient strip front portion and coöperating flat spring strip members having overlapping portions, one piece connector clips encircling said overlapping portions and comprising an integral threaded tightening end, an engaging tightening nut and a coöperating substantially flat tightening portion to be clamped against the flat sides of the buffer strips, and having a hook retaining portion to prevent undesirable disengagement of said threaded tightening end. 80

7. The automobile buffer comprising a resilient strip front portion and coöperating flat spring strip members having overlapping portions, one piece connector clips encircling said overlapping portions and comprising an integral threaded tightening end, and a coöperating substantially flat tightening portion to be clamped against the buffer strips, and having a retaining portion to prevent undesirable disengagement of said 95 threaded tightening end.

8. The automobile buffer comprising a resilient strip front portion and coöperating flat spring strip members having overlapping portions, one piece connector clips encircling said overlapping portions and comprising an integral threaded tightening end, and a coöperating tightening portion to be clamped against the buffer strips. 100

9. The one piece connecting clip adapted for adjustably connecting automobile buffer strips which is formed of round stock bent to closely encircle the buffer strips and formed with a threaded tightening end with which a tightening nut may engage and which is formed with a coöperating integral tightening member having a substantially flat tightening nut engaging portion through which said tightening end passes and opposite the buffer strips to be clamped thereto 115 and having a hook form extending sufficiently around the threaded tightening end to prevent it undesirably moving away from the opposite closed end of the clip.

10. The one piece connector clip adapted for adjustably connecting automobile buffer strips which is formed of round stock bent to closely encircle the buffer strips and formed with a threaded tightening end with which a tightening nut may engage and which is formed with a coöperating integral tightening member having a nut engaging portion through which said tightening end passes and opposite the buffer strips to be clamped thereto and extending sufficiently 120 125 130

around the threaded tightening end to prevent it undesirably moving away from the opposite closed end of the clip.

11. The one piece connecting clip adapted for adjustably connecting automobile buffer strips which is bent to encircle the buffer strips and formed with a threaded tightening end with which a tightening nut may engage and which is formed with a coöperating integral tightening member having a nut engaging portion opposite the buffer strips to be clamped thereto and extending sufficiently around the threaded tightening end to prevent it undesirably moving away from the opposite closed end of the clip.

12. The one piece connecting clip adapted for adjustably connecting buffer strips which is formed of round stock bent to closely encircle the buffer strips and formed with a threaded tightening end with which a tightening nut may engage and which is formed with a coöperating integral tightening member having a substantially flat tightening nut engaging portion through which said tightening end passes and opposite the buffer strips to be clamped thereto and suffi-

ciently embracing the threaded tightening end to prevent undesirable lateral movement thereof.

13. The one piece connecting clip adapted for adjustably connecting buffer strips which is bent to closely encircle the buffer strips and formed with a tightening end with which a tightening device may engage and which is formed with a coöperating integral tightening member having a substantially flat tightening device engaging portion through which said tightening end passes and opposite the buffer strips to be clamped thereto and sufficiently embracing the threaded tightening end to prevent undesirable lateral movement thereof.

14. The one piece connecting clip adapted for adjustably connecting buffer strips which is bent to closely encircle the buffer strips and formed with a tightening end with which a tightening device may engage and which is formed with a coöperating integral tightening member having a substantially flat tightening device engaging portion opposite the buffer strips to be clamped thereto.

GEORGE ALBERT LYON.
